AIR CONDITIONING STRUCTURE

Herman W. Kleist, Chicago, Ill., assignor to Dole Refrigerating Company, Chicago, Ill., a corporation of Illinois

Application November 4, 1950, Serial No. 194,141

2 Claims. (Cl. 62—6)

My invention relates to an improvement in air conditioning and has for one purpose to provide improved air conditioning equipment.

Another purpose is to provide an improved method of air conditioning.

Another purpose is to provide improved means for cooling an intermediate cooling medium for circulation through the space to be cooled.

Other purposes will appear from time to time in the course of the specification and claims.

I illustrate my invention more or less diagrammatically in the accompanying drawings in which

Figure 1 is a vertical section through a more or less diagrammatically indicated dwelling to which my air conditioning equipment and system are applied.

Figure 2 is a similar section on an enlarged scale illustrating part of a variant air conditioning installation.

Figure 3 is a section on an enlarged scale on the line 3, 3 of Figure 2.

Figure 4 is a section through a variant form of cooling member.

Figure 5 is a plan view with parts in horizontal section illustrating an intermediate heat exchange member employed in my system; and

Figure 6 is a section on the line 6, 6 of Figure 5.

Like parts are indicated by like symbols throughout the specification and drawings.

Referring first to Figure 1, A generally indicates a housing or building the interior of which is to be air conditioned. 1 generally indicates the lower floor or cellar area and 2, 2 indicates individual dwelling rooms. 3 indicates an outside installation space and 4 an inside or cellar installation space or room.

B generally more or less diagrammatically indicates a heat exchange member which is illustrated in greater detail in Figures 5 and 6. It may include, for example, heat insulated walls 5 and a removable heat insulated cover 6. 7 is a source of supply of water to be cooled. It is indicated as a pipe passing through one of the walls 5 and communicating with a manifold 8 having a plurality of downwardly inclined spouts 9. 10 is a runoff pipe from which cold water can be withdrawn, for example, by any suitable pumping means 11 illustrated in Figure 1. The pump 11, driven from any suitable power source not shown, is effective to supply adequately cooled water along the water delivery pipe 12. Referring to the details of the heat exchange member B, I find it advantageous to employ a plurality of cold plates individually indicated as 14. Each plate is formed of side walls sealed to their edges to close an inner space in such fashion that it is liquid and gas tight. This inner space is indicated, for example, at C in Figure 6. Within this space I illustrate a coil 16 through which a volatile refrigerant may be circulated. Each such coil has an inlet end on connection 16a and an outlet end on connection 16b. I may advantageously maintain a less than atmospheric pressure within the space C, for example, by withdrawing air through any suitable fitting 17 through which air can-

2

not inwardly pass into the space C. An advantage of providing a pressure differential is that the flexible metal side walls of each plate 14 are drawn firmly inwardly against the coil 16, or against any suitable spacers, if spacers are used. The plates are thus maintained flat, or to a predetermined exterior form, with the evaporator coil 16 in proper heat transfer relation with the walls of the plate.

It will also be understood that I may provide a suitable eutectic as a storage or heat fly wheel means. This eutectic partially or substantially fills the space within the plate and about the coil 16. Such eutectics have the characteristic of freezing or solidifying at a predetermined temperature. They constitute, in effect, a supply of cold, which will absorb heat for a substantial period, after the termination of evaporation or cycling of the volatile refrigerant in the evaporating coil 16.

In order to supply the volatile refrigerant to the plates, I may employ a compressor 20 located within a ventilated housing 21 in the outside work space 3. 22 is any suitable motor for actuating the compressor 20. 23 is any suitable condenser. 24 is the high pressure delivery line along which the condensed refrigerant is delivered under pressure toward the plates. 25 indicates any suitable pressure reduction valve or assembly from which delivery ducts 26 may extend to each of the plates 14. 27 is any suitable common passage or manifold to which the outlets 16b of the various plates deliver. 28 is the return or suction pipe to the compressor 20. It will be understood that when the refrigerant is delivered to the plates, it evaporates and abstracts heat from the water delivered along the passage 7 and by the nozzles 9. The pressure at which the refrigerant evaporates is so related to the eutectic that the eutectic within the plates freezes solid. 35 Also a layer of ice is formed along and across each face of each of the four plates 14. The thickness of the ice layer may be controlled to permit the passage of water along the spaces between the plates and also along the spaces between the outside plates and the insulated walls 5. One of the nozzles 9 is aligned with each such space and delivers water or any other suitable liquid medium therethrough. The thickness of the layer of outside ice may be controlled by any suitable means. I may employ, for example, a temperature responsive element or bulb shown at 30, supported on any suitable spacer or support 31, the bulb being suitably connected with the motor 22 or with any suitable control means or circuit for the motor 22. Thus when the ice layer approaches or reaches the bulb 30, the motor 22 will cease to drive the compressor 20, and the cycling of refrigerant through the coils 16 ceases. However, the ice outside of the plates and the eutectic within the plates serves to maintain a substantially constant temperature in the water or other liquid medium which is drawn by the pump 11 and delivered thereby along the supply pipe 12. This water can be piped to any suitable supplemental heat exchange members 35. These are shown as arranged in Figure 1 in the various individual rooms. Each such member may include finned coils 36, controllable louvers 37 and any suitable air delivering motor and fan 38. Thus, in the embodiment of my invention, shown in Figure 1, a liquid or fluid medium is cooled to a predetermined temperature and is piped, at that temperature, to various points of use. The medium then is put into heat exchange relation with air in the particular rooms to which the medium is piped. While a fan and finned coil assembly is satisfactory and practical, I do not wish to be limited to any specific heat transfer means in the individual rooms. 55 My invention may also be practically applied to houses where the air is heated by any suitable furnace and is delivered along hot air ducts to individual rooms. I illustrate more or less diagrammatically in Figure 2 an ar-

angement of that type. With reference to Figure 2, 40 indicates any suitable furnace shown as provided with a fan 41 driven by a motor 42. Air is drawn by the fan through suitable filters 43 and is delivered through any suitable plenum chamber 44 whence it passes by any suitable outlet ducts 45, 45 to individual louvered outlets 46. The air to be cooled may be drawn from the room space 47 through any suitable outlet 48 and along the duct 49 to any suitable plenum chamber 50. This plenum chamber or return air passage is normally in direct communication with the inlet side of the fan 41. When the system is being used to heat the housing, I may, for example, move the valve or flap 51 to the position in which it is shown in dotted line in Figure 2. However, when the furnace 49 is not in use for a heating purpose, I may drop the flap 51 to the full line position of Figure 2. The air is then deflected through any suitable passage or by-pass 53. In this by-pass I position the finned coil assembly generally indicated as 54 and shown in some detail in Figure 3. Cold water may be delivered to it by the pipe 55, extending from the heat exchange unit or assembly 56 which will be understood to be as shown in Figures 5 and 6. The used water is returned to the heat exchange assembly 56 through any suitable pipe 57. Any suitable valving may be employed as at 55a and 57a, for interrupting the passage of water through the finned coil assembly 54.

In Figure 4 is illustrated a modified form of cooling or heat exchange member. It includes, for example, end manifolds 60 and 61 connected by transversely extending parallel cross pipes 62 which are suitably finned as at 63.

It will be realized that whereas I have described and shown a practical and operative device, nevertheless many changes may be made in size, shape, number and disposition of parts without departing from the spirit of my invention. I therefore wish my description and drawings to be taken as in a broad sense illustrative or diagrammatic rather than as limiting me to my specific showing herein.

The use and operation of my invention are as follows:

I employ what is in effect a two-stage heat exchange system for heating space. This system includes the following mechanisms or steps:

A fluid medium such as water supplied for domestic use is cooled to a predetermined delivery temperature. 45 I preferably cool it by passing it through a heat exchange member or group of members in which a eutectic is employed within one or more plates as a storage medium and the storage effect is further increased by the provision of ice layers through which the medium, or water 50 to be cooled, is directed. Where there is a substantial call for refrigeration, the cycling of the volatile refrigerant may be frequent or almost continuous. But at low load, cycling may be infrequent and the eutectic and the ice serve to maintain the delivered medium at the desired predetermined temperature.

This medium may be used either to supply individual room heat exchange members, or it may be used to cool the air delivered by a single delivery means. Where a house heating system with air ducts is employed in connection with a plenum chamber and fan, my system is

well adapted to cooling the entire supply of air delivered to one or to a number of rooms.

I claim:

5 1. In an enclosure cooling system with stand-by refrigeration, a plurality of generally upright parallel spaced evaporation elements, each having an evaporator coil enclosed in a plate, means for intermittently cycling a volatile refrigerant through the coils, means for obtaining stand-by refrigeration including a water container surrounding the evaporator elements so that its interior is in heat exchange relationship with them, means for circulating cool water through the container and withdrawing it, including a water circuit having a water run-off in liquid communication with a heat exchange member, the adjacent faces of the plates and sides of the container defining a plurality of parallel water passages, water return spouts on the opposite side of the container from the run-off and generally aligned with the water passages, each evaporator element being filled with a eutectic surrounding the coil for obtaining additional stand-by refrigeration, means for controlling the cycling of the refrigerant in response to temperature variations in the container adapted to terminate the refrigerant cycling when a predetermined layer of ice has accumulated on the plates, and means for maintaining a heat exchange relation between said heat exchange member and the air to be cooled in the enclosure.

20 2. In an enclosure cooling system with stand-by refrigeration, a plurality of generally upright parallel spaced evaporation elements, each having an evaporator coil enclosed in a plate, means for intermittently cycling a volatile refrigerant through the coils, means for obtaining stand-by refrigeration including a water container surrounding the evaporator elements so that its interior is in heat exchange relationship with them, means for circulating cool water through the container and withdrawing it, including a water circuit having a water run-off in liquid communication with a heat exchange member, the adjacent faces of the plates and sides of the container defining a plurality of parallel water passages, water return openings on the opposite side of the container from the run-off and generally aligned with the water passages, each evaporator element being filled with a eutectic surrounding the coil for obtaining additional stand-by refrigeration, means for controlling the cycling of the refrigerant in response to temperature variations in the container adapted to terminate the refrigerant cycling when a predetermined layer of ice has accumulated on the plates, and means for maintaining a heat exchange relation between said heat exchange member and the air to be cooled in the enclosure.
